The ornamental design for a laser scanner, as shown and described.

DESCRIPTION

FIG. 1 is a perspective view of a first embodiment of a laser scanner constructed in accordance with the invention;

FIG. 2 is a front elevational view of the 1 laser scanner shown in FIG. 1, the rear elevational view being identical to the front elevational view;

FIG. 3 is a side elevational view of the laser scanner shown in FIG. 1;

FIG. 4 is a top plan view of the laser scanner shown in FIG. 1;

FIG. 5 is a perspective view of a second embodiment of a laser scanner constructed in accordance with the invention;

FIG. 6 is a front elevational view of the laser scanner shown in FIG. 5, the rear elevational view being identical to the front elevational view;

FIG. 7 is a side elevational view of the laser scanner shown in FIG. 5; and,

FIG. 8 is a top plan view of the laser scanner shown in FIG. 5.
